HELICAL HOLLOW ROTOR PUMP

John B. Wade, Arcadia, Calif., assignor to Food
Machinery and Chemical Corporation, a corpo-
ration of Delaware

Application November 29, 1946, Serial No. 712,918

9 Claims. (Cl. 103—117)

1

This invention relates to improvements in Moineau type pumps.

In the Moineau type pump, shown in U. S. Letters Patent No. 2,028,407, a metal rotor provided with a wide, steeply-pitched helical thread is rotated within a central opening in a rubber stator. This opening has a double internal helical thread so that a series of pockets or closed fluid-tight spaces is formed between the rotor and stator, which move axially from the inlet end of the pump toward the outlet end thereof as the rotor is rotated. Each of these pockets is generated while in communication with the inlet end of the pump and thus sucks fluid therefrom and transports this fluid to and discharges it at the outlet end of the pump where the pocket is contracted until dissipated. This produces a pumping action.

Where Moineau type pumps are disposed vertically, as when installed in wells, the rotor is rotated from the lower end of a drive shaft. The principle of operation of the Moineau type pump causes the axis of mass of the rotor to revolve about the central axis of the stator in the reverse direction to that in which the rotor is rotated. The practice has been to make the rotor solid and turn this out on a lathe to produce the necessary helical thread thereon.

Because of the revolution of the axis of mass of the rotor aforesaid, it has been found expedient to connect the rotor to the line shaft with a flexible coupling. This has served to transmit power from the line shaft which rotates about a stationary axis to the rotor which rotates about a reversely revolving axis. At low speeds no difficulty results from this revolution of the rotor. It is the practice in well pumps, however, to turn the rotor 1500 R. P. M. or better. The vibration produced by rotating a solid metal rotor at such speeds is excessive and tends to loosen up the connections of the pump assembly and crystallize the metal parts thereof.

It is accordingly an object of my invention to provide a Moineau type pump in which this excessive vibration is eliminated.

The manufacture of rotors for Moneau pumps individually on a lathe is a laborious, expensive process. Machinery has been provided for making these automatically but this has been so expensive to produce as not to greatly reduce the cost of the rotors.

It is another object of my invention to provide a rotor for a Moineau pump and a method for producing the same whereby said rotors may be made at a relatively low cost.

2

A considerable portion of any flexible drive coupling used for driving the rotor of a Moineau pump revolves reversely with the rotor and the lower portion of this coupling revolves over substantially the same path. It is therefore important in reducing the vibration caused by this revolution of the rotor to reduce to a minimum the weight of the connection between the coupling and the rotor.

Yet another object of my invention is to provide a combination coupling and rotor in which the connection between the coupling and the rotor is effected by means much lighter than originally employed for this purpose yet without sacrificing essential strength in the connection.

It has been recognized in the art to which this invention relates, and indeed is even pointed out in the aforementioned U. S. Letters Patent, that it is preferable for the rotor of a Moineau pump to have a density which is practically equal to the density of the fluid in which it operates in order to obtain a perfect equilibrium. Heretofore, however, no way has been discovered of producing a practical Moineau type pump rotor which will have such a low density.

It is another object of this invention, therefore, to provide a rotor for a Moineau type pump which will meet the exacting structural requirements of accuracy in helical contour and resistance to damage under operating conditions but which, nevertheless, will have substantially the same specific gravity as the liquid in which the rotor operates.

Yet another object is to provide such a rotor which will be comparable in serviceability to the lightest rotors previously available, which were turned from solid bar stock and then provided with an axial cylindrical bore, and which have a specific gravity greatly in excess of that of water.

The manner of accomplishing the foregoing objects as well as further objects and advantages will be made manifest in the following description taken in connection with the accompanying drawings in which:

Fig. 1 is a diagrammatic longitudinal sectional view of a Moineau pump incorporating a preferred embodiment of my invention.

Fig. 2 is an enlarged view of the novel rotor of my invention and illustrates the connection between this rotor and the flexible coupling associated therewith.

Fig. 3 is a vertical elevational view on the same scale as Fig. 2 and partly broken away to illustrate the means for connecting the upper end of the flexible coupling with the line shaft.

Fig. 4 is a view similar to Fig. 3 illustrating a modified means for connecting the lower end of the flexible coupling with the rotor.

Fig. 4A is a view similar to Fig. 4 illustrating another modified means for connecting the rotor and coupling.

Fig. 5 is a plan view of a novel mold of my invention opened as when commencing operations.

Fig. 6 is a perspective view of said mold when so opened.

Fig. 7 is a perspective view of one of the clamping rings employed in connection with said mold.

Fig. 8 is a rotor lapping machine employed in performing the method of my invention.

Fig. 9 is a fragmentary detail view taken on the line 9-9 of Fig. 8.

Fig. 10 is a front elevational view of the aforesaid mold with the latter opened and illustrating the insertion into said mold of a section of tubing when starting to perform the method of my invention.

Fig. 11 is a vertical sectional view of said mold illustrating the manner of applying the clamping rings thereto in performing the method of my invention.

Fig. 12 is a vertical sectional view of said mold and illustrating the consummation of the rotor-shell forming operation in the method of my invention.

Fig. 13 is an enlarged fragmentary sectional view of the base of the mold of my invention.

Referring specifically to the drawings, my invention is shown therein as embodied in a Moineau pump 10 which is suspended from the lower end of a string of pump tubing 11 in a well 12 having an outer casing 13. The tubing 11 is made up of sections between which are mounted bearing spiders 14 having bearings 15 in which is journaled a rotary line shaft 16.

The pump 10 includes a housing 19 which is threadedly connected with the lower end of the pump tubing 11 and is provided at its lower end with a grating 20 to strain water entering the pump 10. Provided within the housing 19 is a rubber Moineau stator 21 having an opening 22 through which a Moineau rotor 23 extends. The stator 21 and the rotor 23 have the characteristic configurations respectively of the stator and the rotor of the Moineau type pump, in which the opening 22 has a double helical female thread and the rotor 23 has a single male thread of the same pitch length.

The rotor 23 is driven by the shaft 16 through a flexible coupling 25 which connects the lower end of this shaft with the upper end of the rotor.

The outer conformation of the rotor 23 of my invention has a single male thread 26 of exactly that form and pitch as will cause it to produce a pumping action when rotated in the stator 21. This conformation must be mathematically exact within a very small tolerance.

To cause the rotor 23 to be of exceptionally light weight as compared with the Moineau pump rotor formerly in common use I form this of relatively thin sheet material which is preferably a ductile metal. While various methods may be used in producing the rotor 23, I have found it preferable to form this by expanding a ductile annealed steel tube into conformity with a mold, the cavity of which has a shape corresponding to the desired shape of the rotor 23, although slightly larger in radial dimensions so that when pressure is relaxed from the interior of the tube the latter will contract to approximately exactly

the desired shape of the rotor 23. This tubular shell 30 comprises the main body of the rotor 23 and is produced in the following manner:

The apparatus for manufacturing the shell 30 includes a mold 35 and a lapping machine 36, these being illustrated in Figs. 6 and 8 respectively. The mold 35 is for forming the shell 30 into approximately its desired shape and the lapping machine is for the purpose of perfecting the outer contour of the shell 30.

The mold 35 includes a base 40 which is adapted to be secured by screws 41 onto a pair of rails 42 so that a central boss 43 of the base extends downwardly between the rails 42. These rails are connected by shafts 44 on which are pivoted eye bolts 45.

The base 40 has a shallow upward boss 48 which has the same outside diameter as a mold body 49 mounted thereon. The base 40 has a hole 50 extending upwardly therein, this hole having a counter-bore 51 with an enlargement 52 at its upper end adapted to form part of a mold cavity 53 provided in the mold body 49.

Extending upwardly through the hole 50 is a hydraulic injection pipe 54 having a cap 55 screwed onto its upper end. The cap 55 has a squared end 56 and is centrally apertured to allow hydraulic fluid to be delivered from the pipe 54 into the interior of the mold. Surrounding the pipe 54 within the counter-bore 51 beneath the cap 57 is a washer 58 and a rubber packer 59. It might be noted here that the diameter of the counter-bore 51 is such as to snuggly receive the lower end of a tube 65 employed in the process and the washer 58 and the packer 59 snuggly fit the interior of this tube when so received.

The mold body 49 is formed of a low temperature casting metal and it originally is cast as a unit about a turned master rotor having exactly the configuration which it is desired to produce in the rotor 23. The master rotor is then screwed out of the casting and the latter is sawed into three segments 66, 67 and 68. These segments are then provided with radial plates 69, 70 and 71, the inner edges of which are ground to accurately complement the surfaces of the mold cavity 53 formed in the segments 66, 67 and 68 of the mold body 49 when the latter was originally molded.

The plates 69, 70 and 71 are slightly thicker than the kerf formed by the saw when dividing the mold body into these segments so that the mold cavity 53 is slightly larger, as measured from the axis thereof, than the rotor shell 30 which it is desired to produce therein. This, as previously explained, is due to the fact that in forming the shell 30 in the mold 35, tube 65 is expanded hydraulically and allowance must be made in the size of the mold cavity 53 for the inevitable contraction of the tube 65 away from the surfaces of the mold cavity 53 when the hydraulic pressure inside the tube is relaxed.

The segment 66 is fixed on the boss 48 and the segments 67 and 68 are connected by hinges 72 to the segment 66. Annular ring seats 78, 79 and 80 are provided with the same inside diameter as the external diameter of the mold body 49 when the segments 66, 67 and 68 thereof are swung together. These ring seats are divided as clearly shown in Figs. 5 and 6 and the respective sections thereof secured to the mold segments 66, 67 and 68 so that when these segments are swung together the ring seats 78, 79 and 80 will sur-

round the mold body 49 and provide tapered surfaces adapted to be engaged by the tapered inside surfaces 81 of a series of clamping rings 82, 83 and 84. These clamping rings are adapted to be applied by pounding a block 85 applied successively to various portions of one of these rings, with a mallet 86. Naturally, ring 84, which is the lowermost, is applied first; then ring 83; then ring 82.

To complete the assembly of the mold 35 a mold head 90 is applied to the top of the mold body 49, this mold head having a flange 91 which snugly receives the upper end of the mold body. The mold head 90 has an upwardly extending boss 92 which carries opposite pairs of clamp arms 93 between which the eye bolts 45 extend to clamp down on these arms and thus hold the head 90, the mold body 49 and the base 40 from being separated vertically during the molding operation.

The mold head 90 has a hole 94 in which is formed a counter-bore 95, the latter having an enlargement 96 at its lower end which complements and unites with the upper end of the mold cavity 53.

Extending through the hole 94 and the head 90 is an air relief pipe 97 having a lower head 98 which traps a washer 99 and a packer 100 in the counter-bore 95. The counter-bore is of the same diameter as the counter-bore 51 and the washer 99 and packer 100 are of the same diameter as the washer 58 and packer 59. Thus when the mold 35 is assembled with the annealed steel tube 65 disposed therein, as shown in Fig. 11, and the head 90 applied as shown in Fig. 12, the upper end of the tube 65 extends snugly into the counter-bore 95 and about the washer 99 and packer 100. The pipe 97 is provided with a nut 101 and a manually operable valve 102.

The lapping machine 36 is built on a frame comprising a pair of rigidly spaced channels 110 on which are mounted a motor 111, a lathe head stock 112 and a lathe tail stock 113, the motor 111 being connected by any suitable means such as a belt 114 to the head stock 112. The head stock has a chuck 115 and the tail stock a collar 116, the latter being adapted to center one end of a shell 30 when the opposite end is gripped in the chuck 115.

The motor 111 has a hand switch 120 and an automatic reversing switch 121, the latter being actuated by the longitudinal shifting of a rod 122 which slides in blocks 123 and 124 provided on one of the channels 110. The rod 122 has two arms 125 and 126 which extend horizontally over the space between the two channel arms 110. Adapted to be screwed onto a shell 30 and remain thereon while the latter is being operated on by the machine 36 is a split lapping nut 130 having an arm 131 extending downwardly therefrom with a roller 132 on its lower end which is adapted to ride against one or the other of the channels 110. The nut 130 has a clamping bolt 135 by which the nut can be tightened or relaxed as desired. The nut 130 has internal threads formed by casting the same around the same master rotor which the mold body 49 was formed from so that the nut 130 is adapted to threadedly receive a shell 30 as shown in Fig. 8.

When the switch 120 is closed, the motor 111 starts to rotate the shell 30 in the machine in a direction to cause the nut 130 to travel either to the right or to the left. Switch 121 is so connected that, when, due to this travel, the arm 131 engages the arm 125, the switch 131 is actu-

ated to cause the reversal of the motor 111, thereby reversing the direction of the movement of the nut 130 on the shell 30. This continues until the arm 131 engages arm 126 which actuates the switch 121 to again reverse the motor 111 to cause the nut 130 to return in the opposite direction. Thus the nut 130 is caused to ride back and forth on the shell 30 so that by placing a grinding compound between the nut and the shell and keeping the nut snugly tightened up on the shell, the latter will be lapped into conformity with the nut 130.

Operation

15 While the tube 65, of which the rotor 23 is formed, may be made of any of a variety of materials, it has been found preferable to use a metal which is resistant to corrosion by the liquid to be handled in the pump in which the rotor is to be employed and then coating the rotor with a layer of chromium applied electrolytically. Among the metals suitable for this use, "Chromium-nickel 18-18" stainless steel has been found preferable. Tubing of this material which is 20 seamless is preferred, although it is practical to use a welded tube from which the flash has been removed.

The tube 65 is cut to the proper length so that its lower and upper ends extend into the counter-bores 51 and 95 and against the bottom shoulders respectively thereof, when the mold 35 is completely assembled as shown in Fig. 12.

After the tube 65 has been inserted as shown in Fig. 11, and before the mold head 90 is applied, a wrench is inserted through the tube 65 and the squared end 56 of the cap 55 turned to screw this onto the pipe 54 and expand the packer 59 within the lower end of the tube 65. After the head 90 has been applied, this is clamped 35 down as shown in Fig. 12 by swinging the eye bolts 45 into vertical position and screwing the nuts thereof downwardly against the clamp arms 93. The nut 101 is then rotated to lift the pipe head 98 and thus expand the packer 100 in the 40 upper end of the tube 65.

Before the tube 65 is inserted into the mold and the latter assembled thereabout, as just described, the tube is subjected to a thorough annealing by heating this to a cherry red and then 45 quenching it in water.

With the tube thus annealed and assembled with the mold and with the air bleeder valve 101 open, the pipe 56 is connected to a high pressure hydraulic pump and the latter operated to inject liquid through the pipe 56 and cap 57 into the interior of the tube 65. The valve 101 is left open until the liquid rises, fills the tube 65, and starts to discharge from the valve, whereupon the latter is closed.

60 As the hydraulic pressure in the tube increases beyond the capacity of the tube 65 to resist distortion, the latter is expanded outwardly to partial conformity with the mold cavity 53.

Owing to the tendency of a tube 65 of this particular material to burst when attempting to expand it into complete conformity with the mold cavity 53 in one stage, I have found it preferable to employ several stages in expanding the tube before finally reaching the desired shape, and removing the tube from the mold and annealing the same between successive stages in the expansion thereof.

When returning tube 65 to the mold after it has been thus partially expanded and removed for annealing, it must be returned in exactly the

same relation with the mold as it had before it was removed from the latter. In accomplishing this, I have found it useful to provide a pair of tongs 140 (see Fig. 10) for rotating the tube 65 to bring suitable marks provided for this purpose on the tube and the mold into registry.

As an example of the diameter and gauge which is desirable in the tube 65 for the purpose of my invention I have found that in making a rotor known as "No. 5 Moineau" rotor which has a diameter of 2.008" after plating, a tube 65 which is of 16 gauge material with a 1 1/4" outside diameter is quite suitable.

Escape of liquid from opposite ends of the tube 65 during one of the expanding operations is prevented by the expansion of the packers 59 and 100 in the lower and upper ends of the tube 65 where these are disposed in the counter-bores 51 and 95 respectively. The higher the pressure of the liquid in the tube 65 the tighter the seal formed by the packers 59 and 100 to prevent the escape of liquid from the tube.

To remove the tube 65 from the mold 35 after it has been partially or fully expanded to form a rotor shell 30, the process of assembling the tube 65 with the mold and above described is merely reversed.

When the shell 30 has been formed as completely as it is possible to do this in the mold 35, there still remain imperfections in the outer surface of the shell 30 which must be eliminated and this surface then provided with a protective coating of chromium.

The perfecting of the contour of the thread 26 on the rotor shell 30 is accomplished in the lapping machine 36. Being formed directly from a master rotor of the exact shape which is desired to be given to the rotor shell 30, the lapping nut 130, when supplied with a grinding compound and put to work on the shell 30 in the machine 36, as already described, will smooth the outer surface of the shell 30 and bring this into very close approximation of the conformation of the master rotor.

The lapping operation is also preferably carried on in three stages with coarse, medium and fine grinding compounds, the final stages being a polishing operation.

The lapping and polishing of the rotor shell 30 is carried out with a view to finishing with the rotor being at least .004" less in diameter than the desired final size of the rotor shell. A coating of chromium is then applied electrolytically to the outer surface of the rotor shell which may be anywhere from .002" to .004" in thickness depending upon what it is necessary to add to the diameter of the shell 30 to give it the outside diameter it should have in order to cause it to function properly in the stator 21.

This chromium is applied to the shell 30 in the same manner as it is now customary to apply chromium to shafts where these rotate in water lubricated rubber bearings.

The upper and lower tubular ends 145 and 146 of the shell 30 remain cylindrical without changing diameter throughout the expansion of the tube 65. The bottom tubular end 146 may be shortened as shown in Fig. 2 and closed by a plug 148 welded therein. The upper tubular end 145 is preferably utilized to form a connection with the lower end of the flexible coupling 25. It is desirable, of course, to eliminate as much weight as possible not only in the rotor 23 itself, but in the connection between this and the coupling 25. Three modes of performing this con-

nection are illustrated herein, one of these being shown in Fig. 2, another in Fig. 4, and still another in Fig. 4A.

The coupling 25 is of the general type disclosed in U. S. Letters Patent of James M. Hait, No. 2,346,426, issued April 11, 1944, on "Flexible rotary drive coupling." This type of coupling comprises a steel cable 171, the upper end of which extends into and is securely held in a cable socket 172 of a coupling head 173 having a screw receptacle 174 which screws onto the threaded lower end 175 of the shaft 16.

In Fig. 2 the cable 171 is shown as connected to the rotor 23 by the swedging of a light steel socket 176 thereabout, and then welding this socket, which constitutes a lower coupling terminal member, into the upper tubular end 145 of the shell 30. The mouths 177 and 181 of the sockets 172 and 176 are flared and the entire cable 171 and substantial portions of the sockets 172 and 176 and the rotor neck 145 are covered with a rubber sheath 185 which is vulcanized in place so as to extend into the flared socket mouths 177 and 181 and thus form a cushion preventing the cable 171 being sharply bent adjacent the sockets 172 and 176.

It is frequently desirable to disconnect a rotor 23 from a flexible coupling 25 where one of these needs to be replaced while the other is still good. 39 This is made readily possible by the construction shown in Fig. 4. In this construction the upper tubular end 145 of the shell 30 is cut off rather short and receives a nipple 190 formed on the lower end of a short internally threaded socket 191 having the same outside diameter as the tubular shell end 145. The two are then welded together so as to permanently unite the socket 191 with the rotor shell 30. When this construction is used the lower end of the flexible coupling 25 has a socket 194 which receives and is swedged about the lower end of the cable 171 and in turn is provided with threaded male member 195, which screws into the threaded socket 191.

As shown in Fig. 4 the flexible coupling 25 and 45 member 194 have the same outside diameter as the socket 191 and upper tubular end 145 of the shell 30. Thus there is a minimum of interference with the flow of water from the pump 10 upwardly through the pump tubing 11.

The rotor 23 of my invention weighs approximately one pound, whereas the solid rotor made of stainless steel, which has preceded it in common use, weighs seven pounds. Moreover, since the solid rotor must be turned from a solid piece 55 of stainless steel which weighs ten pounds, it is readily seen that the method of my invention offers an opportunity to produce a Moineau pump rotor with a saving of about 90% in the amount of the critical materials required. It is further evident that by my method Moineau pump rotors 60 may be produced at a great saving in expense over the cost of producing rotors by turning these from a solid piece of stainless steel.

A still more significant advantage of the rotor 65 23, however, is its extremely low weight and the marked decrease in the amount of vibration produced by my rotor over the vibration produced with solid rotors. The extreme low weight of the rotor 23 results, of course, from its being formed of a shell of substantially uniform thickness, and its being closed at its lower end by the plug 148 and at its upper end by its connection with the coupling 25 so that the rotor remains hollow or empty, although during its operation 70 it is continuously submerged in a liquid.

Exclusion of this liquid from the lower end of the rotor is effected by the welding of plug 148 in the tubular lower end 146 of the rotor 23. The closing of the upper end of the rotor 23 so as to effectively prevent the admission of liquid to the hollow interior thereof, (in the form of the rotor shown in Fig. 2) is accomplished by completely enclosing the coupling cable, exposed portions of the socket 176, and the upper tubular end 145 of the shell 30 within the rubber sheath 185 and vulcanizing this sheath to these metal parts as shown in Fig. 2.

The welding of the nipple 190 into the upper tubular end 145 of the shell 30 of the rotor 23 also makes a liquid tight connection between the upper end of the rotor 23 and the threaded socket 191. When the latter is screwed into the threaded male member 195, a suitable sealing compound, such as paint, is used on the threads to make the connection between the coupling socket 194 and the threaded socket 191 on the rotor, thereby forming a liquid tight closure for the upper end of the rotor.

The closing of the lower end of the rotor 23 by welding the plug 148 therein hermetically seals the lower end of the rotor against the admission of liquid and it has been found preferable to also hermetically seal the upper end of the rotor in a similar manner as shown in Fig. 4A. In this view the rotor 23 is shown fitted with a threaded socket 196 having a plug 197 which fits into and is welded to the upper tubular end 145 of the shell 30 of the rotor 23 so as to hermetically seal the upper end of the rotor against the admission of liquid into the hollow interior thereof.

This application is a continuation in part of my co-pending U. S. Letters Patent application, Serial No. 553,626, filed September 11, 1944, for "Moineau pump coupling-rotor and method of making same," now abandoned.

The rotor 23 of my invention of the type shown in Fig. 4A and which is made in accordance with the foregoing data is substantially of the same specific gravity as water, which is the liquid that Moineau pumps are ordinarily employed for handling.

The claims are:

1. A gear mechanism adapted for use as a pump and comprising: a stator having a female-threaded chamber, the latter having an inlet and an outlet communicating therewith at axially spaced points; and a thin-walled, male-threaded rotor comprising a tube which, throughout substantially its entire length, is hollow and has walls of substantially uniform thickness, said tube being plugged at opposite ends so as to seal the hollow interior thereof against the admission of liquid thereto and being revolvably disposed in said chamber and always in contact therewith in any cross section, the number of female threads of the stator exceeding by one unit the corresponding number of male threads on the rotor, a closed fluid-tight axial space being comprised between said stator and rotor wherein the fluid is contained, rotation of said rotor generating a continuous series of said spaces, each such space being in communication with said inlet while being generated, said rotation causing each such space to then travel in an axial direction until coming into communication with said outlet and then causing said space to be contracted until dissipated, fluid thus being transferred from said inlet to said outlet, said rotor, because of its lightness, producing a radically less amount of vibration than is produced by a

like rotor of solid construction when so rotated in said stator.

2. A gear mechanism adapted for use as a pump and comprising: a stator having a female-threaded chamber, the latter having an inlet and an outlet communicating therewith at axially spaced points; a thin-walled male-threaded rotor comprising a tube which, throughout substantially its entire length, is hollow and has walls of substantially uniform thickness, said tube being plugged at opposite ends so as to seal the hollow interior thereof against the admission of liquid thereto, said rotor being revolvably disposed in said chamber and always in contact therewith in any cross section, the number of female threads of the stator exceeding by one unit the corresponding number of male threads on the rotor, a closed fluid-tight axial space being comprised between said stator and rotor wherein the fluid is contained, rotation of said rotor generating a continuous series of said spaces, each such space being in communication with said inlet while being generated, said rotation causing each such space to then travel in an axial direction until coming into communication with said outlet and then causing said space to be contracted until dissipated, fluid thus being transferred from said inlet to said outlet, the plugging means at one end of said rotor constituting a detachable connection between the rotor and a driving means therefore, said rotor, because of its lightness, producing a radically less amount of vibration than is produced by a like rotor of solid construction when so rotated in said stator.

3. A hollow male threaded pump rotor of relatively light weight adapted to rotate at high speeds in a female threaded stator whereby said rotor is caused to revolve about an axis eccentric to the center of mass of said rotor and in the opposite direction to said rotation, said rotor comprising a tubular shell which, throughout substantially its entire length, is hollow and has walls of substantially uniform thickness, said shell being sealed at its opposite ends against the admission of liquid thereto, the means for sealing one end of said rotor having means thereon for connecting said rotor with a driving means therefor, said rotor, because of its lightness, producing a radically less amount of vibration than is produced by a like rotor of solid construction when so rotated in said stator.

4. A combination as in claim 3 in which one end of said rotor has an axially disposed integral tubular neck, the sealing means connecting said rotor with a driving means therefor being housed within and bonded to said neck.

5. A combination as in claim 4 in which said sealing means housed within and bonded to said tubular neck comprises a cup which provides a detachable connection between said hollow rotor and said driving means.

6. A hollow pump rotor as defined in claim 3 in which said connecting means comprises a flexible cable having a head permanently united therewith, said head being also permanently bonded with one end of said rotor whereby rotation of said cable is transmitted to said rotor and said head forms the sealing means for said end of said rotor.

7. A hollow pump rotor as defined in claim 3 in which said connecting means comprises a flexible cable having a head permanently united therewith and with one end of said rotor to form the sealing means therefor and to connect said

11

cable to said rotor, said end of said rotor and said head and said cable being covered by a sheath of soft rubber molded thereon and bonded thereto.

8. A hollow pump rotor as defined in claim 3 in which the means for sealing one end of said rotor and connecting the rotor with a driving means therefor includes an internally threaded cup which fits within said rotor end and is bonded thereto; a male-threaded drive coupling head adapted to screw into said cup; and a flexible drive coupling element united with said head.

9. A gear mechanism adapted for use as a pump and comprising: a stator having a female-threaded chamber, the latter having an inlet and an outlet communicating therewith at axially spaced points; a hollow, thin-walled male-threaded, tubular rotor revolvably disposed in said chamber and always in contact therewith in any cross section, the number of female threads of the stator exceeding by one unit, the corresponding number of male threads on the rotor; a plug closing one end of said rotor; bearing means disposed concentrically with said stator; a shaft journaling in said bearing means and spaced axially from said rotor; a flexible coupling comprising two heads connected by a flexible cable, one of said heads being fixed upon

5 said shaft and the other of said heads extending into the other end of said hollow rotor and being bonded thereto to seal the same against the admission of liquid thereto and to transmit torque from said coupling to said rotor; and a rubber coupling sheath which covers and seals the connection between said hollow rotor and said coupling.

JOHN B. WADE.

Certificate of Correction

Patent No. 2,464,011.

March 8, 1949.

JOHN B. WADE

It is hereby certified that errors appear in the printed specification of the above numbered patent requiring correction as follows:

Column 2, line 14, for the word "originally" read *ordinarily*; lines 50 and 51, for "associate dtherewith" read *associated therewith*; column 6, line 23, for "18—18" read 18—8; column 8, line 70, for "fromed" read *formed*; column 9, line 32, for "en d145" read *end 145*;
and that the said Letters Patent should be read with these corrections therein that the same may conform to the record of the case in the Patent Office.

Signed and sealed this 9th day of August, A. D. 1949.
